UNITED STATES PATENT OFFICE.

ALBERT E. BECK, OF ANACOSTIA, DISTRICT OF COLUMBIA, ASSIGNOR OF ONE-HALF TO MARK REID YATES, OF WASHINGTON, DISTRICT OF COLUMBIA.

FLAT-CAR.

No. 830,471.

Specification of Letters Patent.

Patented Sept. 4, 1906.

Application filed March 13, 1906. Serial No. 305,877.

To all whom it may concern:

Be it known that I, ALBERT E. BECK, a citizen of the United States, residing at Anacostia, District of Columbia, have invented 5 certain new and useful Improvements in Flat-Cars, of which the following is a specification.

My invention relates to an improvement in flat-cars, and the object is to provide side 10 posts to secure the freight in position upon the floor thereof, which side posts may be swung outwardly when the car is being loaded or lowered upon the car-floor and out of the way when they are not in use. I attain 15 these objects by the construction illustrated in the accompanying drawings, in which—

Figure 1 is a side elevation of the car. Fig. 2 is an end view thereof. Fig. 3 is a detail view 20 in perspective of the post-hinge and socket, showing in dotted lines the different positions of the post. Fig. 4 is a detail view of the car-stringer. Fig. 5 is a top plan view of a portion 25 of the car, showing the posts lowered out of the way. Fig. 6 is a bottom plan view of the posts in the lowered position. Fig. 7 is a detail of a modification.

Like numerals indicate like parts throughout the several views of the drawings.

1 is a flat-car commonly employed in transporting lumber and other freight, and 2 is the floor thereof, laid upon the stringers 3 and end sills 4. At suitable intervals along the sides of the car are located the posts 5, which 35 are pivotally secured to the stringers by means of the hinges 6. The posts are constructed of well-seasoned wood 7, preferably hickory, and are incased in metal 8 of a suitable thickness to prevent swelling from exposure to the 40 elements. Metallic straps or bands 9 and 10 are shrunk around the upper and lower ends of the posts. Each post is provided with a slidable sleeve or strap 11, formed with the projecting ears 12, between which is pivotally secured a tie-rod 13. The posts, which 45 are arranged somewhat out of alignment with the companion-posts upon the opposite side of the car for a purpose which will become apparent later, are tied in pairs by the tie-rods when the car is loaded, and for this purpose the tie-rods on one side of the car carry turnbuckles 14, confined upon them by heading the end of the rods, as at 15, and the tie-rods on the opposite side are threaded on the

ends, as at 16, to engage with the threaded 55 end of the turnbuckles. The slidable sleeves or straps 11 permit the tie-rods to be adjusted to the height of the load upon the car. These rods are disposed at a slight angle to the posts to facilitate their connection, and 60 each post is recessed at 17 to receive the rods when disconnected. These recesses are disposed at an angle to conform to the tie-rods.

Upon the lower ends of the posts are the 65 rectangular slidable sleeves 18, which are confined upon the same by the straps or bands 10. These sleeves are provided with extensions folded downwardly and projecting below the same to form the ears 19, 19, which said ears are provided with registering 70 rivet-holes to receive the rivets 20, which pivotally secure these sleeves to the post-seats 21 and form the hinge-joint between the posts and the car. These post-seats are somewhat larger in cross-section than the sleeves 75 18, which permit the end of the post to be dropped therein when elevated. The construction of hinge-joint just described allows the post to be swung outwardly from the car and lowered to the ground while the car is being loaded, after which the posts are elevated and tied together in the manner heretofore described. These post-seats are rectangular 80 in shape and are strapped to the stringers 3 with their tops on line with the car-floor by 85 means of the U-shaped bolts 22, which are retained in place upon the post-seats by the corrugations 23 thereon. The threaded ends of the said bolts pass through holes in the stringers and receive the nuts 24. 90

To receive the posts when lowered and permit them to lie flush with the car-floor, the stringers are recessed or cut away for a depth equal to the thickness of the flooring, as shown at 25, and of a width to receive the 95 two companion posts. This will be clearly seen in Figs. 3, 4, and 5 of the drawings. The posts are made of just sufficient width to lie flush with the floor when lowered. When the posts are lying upon the car and the tie-rods are secured in their recesses by the pivoted catches 26, they form no obstruction to freight which may be loaded thereon. As shown in the modification illustrated by Fig. 7, these posts may be made entirely of metal, 100 hollow and rectangular in cross-section, as at 27, and of suitable thickness to give rigidity to the post. 105

The straps or bands 28 form shoulders on the posts which rest upon the tops of the slideable sleeves 18 when the posts are in a vertical position with the ends thereof in the post-seats 21. These straps or bands are located sufficiently far from the ends of the posts to allow them to drop to the end of the post-seats. When the posts are to be laid flat upon the car-body, they have to be first removed from the said seats by lifting them clear of the same.

Having thus fully described my invention, what I claim as new, and desire to secure by Letters Patent, is—

15. 1. The combination with a car constructed with an opening in the floor thereof, of a pivotal post attached to the car and adapted to be folded upon the car-floor and into the opening flush with the surface of the floor.
20. 2. The combination with a car constructed with an opening in the floor thereof, of a pivotal post attached to the car and adapted to be folded into the opening flush with the surface of the floor and means for bracing said post in a vertical position to impart rigidity thereto.
25. 3. The combination with a car constructed with an opening in the floor thereof of a post adapted to be folded into the opening flush with the surface of the floor, and a hinge connection between the car and the post comprising a socket member adapted to seat the post when in its vertical position and a sleeve member having a slideable connection with the said post.
30. 4. The combination with a car provided with a channel or opening transversely of the floor, of pivotal posts attached to the sides of the car adjacent to the opposite ends of the channel or opening and adapted to be folded down into the same flush with the surface of the floor and means for bracing the said posts in a vertical position to impart rigidity thereto.
35. 5. The combination with a car provided with a channel or opening transversely of the floor, of pivotal posts attached to the sides of the car adjacent to the opposite ends of the

channel or opening and adapted to be folded down into the same flush with the surface of the floor and adjustable tie-rods on said posts adapted to be connected to brace the posts in a vertical position.

6. The combination with a car and a side post adapted to be folded upon the car, of a hinge connection between the post and the car comprising a socket member rigidly secured to the car-body and a sleeve member pivotally attached to said socket member and adapted to be slidably connected with the post to permit withdrawal of the end of the post from the socket member, and means for limiting the movement of the post within the sleeve member.

7. The combination with a car and a post, of a hinge for securing said post pivotally to the side of the car the said hinge comprising a socket member and a sleeve member, pivotally connected therewith, said sleeve member being slidably attached to the post.

8. The combination with a car and a post, of a hinge for securing said post pivotally to the car, the said hinge comprising a socket member and a sleeve member, pivotally connected therewith, the said sleeve member being slidably attached to the post, and means for securing the hinge to the car.

9. The combination with a car constructed with a transverse opening or channel in the floor thereof of side posts pivotally attached to the said car and adapted to be folded down into the said opening or channel flush with the surface of the car-floor, slideable tie-rods attached to said posts and adapted to be adjusted at different heights upon said posts, recesses in said posts to receive the rods when not in use and means for connecting the tie-rods of opposite posts to brace the latter.

In testimony whereof I have signed my name to this specification in the presence of two subscribing witnesses.

ALBERT E. BECK.
